UNITED STATES PATENT OFFICE.

JOHN WILLIAM RICKERT, OF SOUTH MILWAUKEE, WISCONSIN, ASSIGNOR OF ONE-HALF TO JOHN C. WILLIAMS, OF SOUTH MILWAUKEE, WISCONSIN.

TOBACCO-PIPE.

SPECIFICATION forming part of Letters Patent No. 713,242, dated November 11, 1902.

Application filed April 3, 1902. Serial No. 101,273. (No model.)

To all whom it may concern:

Be it known that I, JOHN WILLIAM RICKERT, a citizen of the United States, residing at South Milwaukee, in the county of Milwaukee and State of Wisconsin, have invented a new and useful Tobacco-Pipe, of which the following is a specification.

The invention relates to improvements in tobacco-pipes.

10 The object of the present invention is to improve the construction of pipes and to provide a simple, inexpensive, and efficient one adapted to afford a clean dry smoke and capable of effectually preventing the nicotine of 15 the bowl from entering the stem of the pipe.

A further object of the invention is to provide a pipe of this character in which the inner end of the stem will be offset from the bottom of the bowl and which will be adapted 20 to have its passages conveniently and thoroughly cleaned.

The invention consists in the construction and novel combination and arrangement of parts hereinafter fully described, illustrated 25 in the accompanying drawings, and pointed out in the claims hereto appended.

In the drawings, Figure 1 is a perspective view of a pipe constructed in accordance with this invention. Fig. 2 is a longitudinal sec- 30 tional view.

Like numerals of reference designate corresponding parts in both figures of the drawings.

1 designates a pipe-bowl having a lower flat 35 face 2 and adapted to support its stem 3 in an elevated position out of contact with the supporting-surface to prevent the outer end of the stem from becoming dirty when the pipe is laid down. The bowl, which may be 40 constructed of wood, composition, or any other suitable material, is provided with the usual tobacco-chamber 4, and it has a lower transverse bore forming a smoke passage or flue 5, which extends rearward through the

45 rear wall of the bowl to provide an exteriorly-accessible outer end, and the lower transverse smoke-flue inclines downward and rearward and is arranged in the same plane as the bottom 6 of the tobacco-chamber, which is in- 50 clined to cause any saliva entering the bowl

through the stem to drain away from the tobacco-chamber toward the rear or outer end of the lower transverse smoke-flue.

The rear wall of the bowl is preferably thickened or enlarged and is provided with 55 an upright ascending smoke passage or flue 7, which extends from the lower transverse smoke-flue to the top of the bowl, where it is exteriorly accessible to permit the pipe to be readily cleaned, as hereinafter explained. 60 The exteriorly-accessible upper end of the ascending smoke-flue is adapted to receive a suitable cleaning device—such as a wire, match-stem, or the like—by means of which any accumulation in the upright ascending 65 flue may be readily removed or forced downward to the lower transverse smoke-flue. The lower transverse smoke-flue is adapted to receive a similar cleaning device, and the accumulation may be removed or forced into the 70 tobacco-chamber of the bowl, from which it may be readily emptied.

The rear enlargement or thickened portion of the bowl is provided with an upper transverse bore 8, forming a stem-opening, which 75 communicates with the ascending smoke-flue at a point above the lower transverse smoke-flue. The smoke passes upward from the bottom of the bowl, through the lower transverse smoke-flue and the ascending upright 80 smoke-flue to the stem-opening, and the nicotine will remain in the bottom of the bowl, thereby enabling the pipe to afford a clean dry smoke, and any saliva entering the pipe through the stem will be caused to drain from 85 the tobacco-chamber by the inclination of the bottom of the tobacco-chamber and the lower transverse smoke-flue. The smoke-flues, which are straight and which intersect or communicate, are adapted to receive a 90 straight cleaning rod or pin, and they are provided at their outer ends with removable closures 9 and 10, preferably consisting of plugs, which are fitted in the upper end of the ascending flue and in the rear end of the 95 transverse smoke-flue 5. The point of intersection of the straight smoke-flues is at the bottom of the bowl and in line with the bottom of the tobacco-chamber, and each flue extends outward to the exterior of the 100

pipe from this point, whereby the bowl of the pipe may be easily and thoroughly cleaned. The removable closures may be arranged in any other suitable manner, and the lower 5 plug or closure 10 may be readily taken out at any time to permit any saliva to drain from the bowl.

It will be seen that the pipe is exceedingly simple and inexpensive in construction, that 10 the straight intersecting smoke-flues, which have exterior accessible outer ends and which are provided with removable closures, are adapted to enable all accumulation to be conveniently and thoroughly removed from the 15 bowl, and that the transverse smoke-flue also forms a drain-opening and is adapted to cause any saliva to flow from the tobacco-chamber and will prevent such saliva from entering the same. Also it will be clear that by lo- 20 cating the pipe-stem above the transverse smoke-flue the nicotine will not rise in the ascending smoke-flue sufficiently to enter the stem before an opportunity is afforded for 25 cleaning the pipe.

What is claimed is—

1. A bowl for tobacco-pipes having an ascending smoke-flue exteriorly accessible at its upper end and fitted with a removable closure, a straight transverse smoke-flue connecting the lower end of the ascending smoke-flue with the bottom of the tobacco-chamber and extending therefrom in a straight line to the exterior of the pipe to permit a straight cleaning device to pass through it into the 30 tobacco-chamber to remove all accumulation, said transverse flue having an exteriorly-accessible outer end and fitted with a removable closure, and a stem-opening communicating with the ascending smoke-flue above 35 the transverse smoke-flue, substantially as described.

2. A bowl for a tobacco-pipe having straight intersecting smoke-flues extending inward from the exterior surface of the bowl and fitted 40 at their outer ends with removable closures, the intersecting of the smoke-flues being adjacent to the bottom of the bowl, one of the flues being in communication with the 45 interior of the tobacco-chamber and extending therefrom in a straight line to the exterior of the pipe to permit a straight cleaning

device to force all accumulation from the flues into the tobacco-chamber, and a stem-opening in communication with the other flue above the plane of the flue which communicates with the tobacco-chamber, substantially 55 as described.

3. A bowl for a tobacco-pipe having a tobacco-chamber provided with a rearwardly-inclined bottom, an ascending smoke-flue 60 exteriorly accessible at its upper end and fitted with a removable closure, a straight transverse flue communicating with the lower end of the ascending smoke-flue, and inclined downward and rearward from the tobacco-chamber in approximately the same plane as the bottom thereof to cause drainage therefrom and extending in a straight line from the said chamber to the exterior of the bowl, to permit a straight cleaning device to force 65 all accumulation from the flues into the tobacco-chamber, said transverse flue being provided at its outer end with a removable closure, and a stem-opening communicating with the ascending flue at a point above the 70 transverse smoke-flue, substantially as described.

4. A bowl for a tobacco-pipe having straight intersecting smoke-flues extending inward from the exterior surface of the bowl and fitted 80 at their outer ends with removable closures, one of the flues being inclined downward and outward from the tobacco-chamber to cause a drainage therefrom to the exterior of the pipe and permitting a straight cleaning 85 device to be passed through it to the tobacco-chamber to remove all accumulation from the flues, and the other smoke-flue extending upward from the inclined flue and permitting a straight cleaning device to be passed 90 from the exterior of the bowl to the inclined flue, and a stem-opening located above the inclined smoke-flue and communicating with the upwardly-extending smoke-flue, substantially as described.

In testimony that I claim the foregoing as my own I have hereto affixed my signature in the presence of two witnesses.

JOHN WILLIAM RICKERT.
